(57) **CLAIM**

We claim the ornamental design for a hand saw, as shown and described.

DESCRIPTION

FIG. 1 is a top, front, right perspective view of a hand saw, embodying the new design;

FIG. 2 is a top plan view thereof;

FIG. 3 is a right side elevation view thereof;

FIG. 4 is a front elevation view thereof;

FIG. 5 is a rear elevation view thereof;

FIG. 6 is a left side elevation view thereof; and,

FIG. 7 is a bottom plan view thereof.

The broken lines shown in the drawings illustrate portions of the hand saw that form no part of claimed design.
